UNITED STATES PATENT OFFICE.

SHUBAEL COTTLE, OF NEW YORK, N. Y.

DESIGN FOR A PURSE.

SPECIFICATION forming part of Design No. 19,591, dated January 21, 1890.

Application filed December 24, 1889. Serial No. 334,881. Term of patent 3½ years.

To all whom it may concern:

Be it known that I, SHUBAEL COTTLE, of the city, county, and State of New York, have invented and produced a new and original Design for Purses, of which the following is a specification, reference being had to the accompanying drawing.

My design is intended to be applied to a purse for carrying money or other small articles. The lower portion A of the purse has the appearance of a bowl, and the upper portion B of said purse has the appearance of a reticulated or woven fabric. The reticulated portion of the design appears to meet the bowl-shaped portion thereof at the straight edge of the bowl. Upon the surface of the

bowl may appear a raised ornamental pattern, and at the edge of the reticulated portion B may appear a series of scallops C or other ornamental finish. The particular ornamental pattern here shown on the bowl-shaped part A and the ornamental edging C are not essential to my design, but may be varied.

I claim—

The design for a purse, substantially as herein shown and described.

SHUBAEL COTTLE.
